UNITED STATES PATENT OFFICE.

ORLANDO DUCKER, OF WASHINGTON, DISTRICT OF COLUMBIA.

STARTING MECHANISM FOR EXPLOSIVE-ENGINES.

1,015,482.

Specification of Letters Patent. Patented Jan. 23, 1912.

Application filed October 10, 1910. Serial No. 586,348.

To all whom it may concern:

Be it known that I, ORLANDO DUCKER, a citizen of the United States, residing at Washington, in the District of Columbia, have invented new and useful Improvements in Starting Mechanism for Explosive-Engines, of which the following is a specification.

Engines of the explosive type are usually started by imparting an initial rotary movement to the crank shaft by hand and this is usually attended with inconvenience and danger.

The present invention provides novel means for supplying a gaseous mixture under compression to the cylinders of a multiple engine and exploding the same, thereby starting the engine without necessitating the operator leaving his seat in the machine.

The present invention relates to multiple engines of the explosive type utilizing liquid fuel for carbureting air as the latter is supplied to the cylinder in succession. In accordance with the invention a tank is supplied containing air under pressure. A header has connection with said tank, valved pipes connect the header with each of the cylinders, a fuel supply pipe has connection with the pipe between the header and the air pressure tank, and a series of valves are interposed in the length of the several pipe connections for proper control of the fluids.

The invention consists of the novel features, details of construction and combination of parts, which hereinafter will be more particularly set forth, illustrated in the accompanying drawing, and pointed out in the appended claim.

Referring to the drawing, forming a part of the application, Figure 1 is a top plan view of a multiple engine of the explosive type provided with starting mechanism embodying the invention. Fig. 2 is a detail view, showing the cylinders, the relative position of the pistons therein and the connections. Fig. 3 is a detail perspective view of one of the plugs for controlling admission of the gaseous mixture into the cylinders.

Corresponding and like parts are referred to in the following description, and indicated in all the views of the drawing, by the same reference characters.

As stated the invention is designed most especially for explosive engines of the multiple type utilizing liquid fuel. The draw-

ing illustrates an engine of this type as applied to an automobile, the engine being of the four cylinder variety and having the usual intake and exhaust. Since the present invention relates solely to the starting mechanism it is not deemed necessary to describe the engine or adjunctive parts in detail, since the starting mechanism may be applied to any type of explosive engine and that shown is of ordinary construction and illustrated to demonstrate the application of the invention.

The numeral 1 designates a tank or other container for receiving air under pressure and this tank may be of any capacity and located in any convenient position.

The numeral 2 indicates a header, which is of conical form. A pipe 3 connects the air pressure tank 1 with the small end of the header 2 and has a valve 4 in its length. A series of pipes 5 connect the large end of the header 2 with the individual cylinders of the engine to supply gaseous mixture thereto when starting the engine. Each of the pipes 5 has a valve 6 and these valves are located close to the respective cylinders and are adapted to be simultaneously operated by means of a rod or bar 7. Normally the valves are closed and when it is required to open the valves the rod or bar 7 is moved inward against the tension of a spring 8, which automatically closes the valves when the part 7 is relieved of the force exerted for operating the same. A pipe 9 leading from the tank containing the gasoline or other liquid fuel connects with the pipe 3 near the header 2 and at a point between said header and the valve 4. The pipe 9 terminates in a nozzle or small outlet 10 so as to deliver a fine jet of gasoline or liquid fuel into the pipe 3 across the path of the air therethrough, whereby said fuel is vaporized. A valve 11 is located in the length of the fuel supply pipe 9. An auxiliary fuel tank 12 is connected with the fuel supply pipe 9 and has a valve 13 in its length. The several valves 4, 11 and 13 are adapted to be operated from any convenient point.

In the operation of the invention the header 2 acts as a mixer besides constituting a manifold for supplying the several pipes 5 with the gaseous mixture. When the engine stops the pistons occupy different relative positions in the cylinders, as indicated most clearly by the dotted lines in Fig. 2. When it is required to start the

engine either one of the valves 11 or 13 is opened, after which the air valve 4 is opened to admit compressed air to the header 2. The compressed air rushing through the pipe 3 past the nozzle 10 draws liquid fuel into the pipe 3 and carries the same into the header where the air and fuel are mixed. The valves 6 are opened momentarily only by a quick action of the rod 7. The gas admitted into the cylinders acts with greatest force on the piston nearest the explosion end of the cylinder and moves said piston, the crank shaft and fly wheel sufficiently to start the engine. The spark being properly adjusted the gas in the cylinder containing the piston on the working stroke is exploded. The air contained in the tank 1 is usually under an approximate pressure of two hundred pounds to the square inch and it is essential that the valves 6 be opened for an instant only, otherwise the pressure of the gaseous mixture will be equalized on all the pistons and no movement result. The auxiliary tank 12 is utilized chiefly when the supply of fuel is low in the main tank and may be dispensed with since the fuel may be drawn from the main tank upon opening the valve 11. If the fuel is to be drawn from the auxiliary tank 12 when starting the engine the valve 11 is not opened, the fuel being drawn from the tank 12 upon opening the valve 13. After the engine has been started the valve 13 is closed and the engine permitted to draw a supply through the usual intake and pipe 14 connected with the pipe 9 leading to the main tank.

From the foregoing description, taken in connection with the accompanying drawing, the advantages of the construction and of the method of operation will be readily apparent to those skilled in the art to which the invention appertains, and while I have described the principle of operation of the

invention, together with the device which I now consider to be the embodiment thereof, I desire to have it understood that the device shown is merely illustrative, and that such changes may be made when desired as are within the scope of the claims appended hereto.

In connection with the above, it is to be particularly noted that the communication between the source of air supplied under pressure and the engine cylinders is direct, and that under these circumstances, in the initial charging of the particular cylinder for starting purposes, there will of necessity be a proportion of air delivered to the cylinder in advance of the mixture of air and vapor. This sufficiently adulterates the charge to prevent a too-rich mixture, hence insuring a proper combustion mixture. Furthermore, in the accompanying specification and claim, the term "jet" is used to indicate a finely divided or minute stream of gasoline, hence being intended to include what is known as a spray or other finely divided stream or streams.

Having thus described the invention what is claimed as new, is:—

In engine starting mechanism of the character set forth, the combination of an air tank, a valved pipe connection between the air tank and the cylinder of the engine, a fuel supply pipe leading from the main tank containing the fuel in bulk connecting with the air pipe and adapted to deliver the fuel thereto in a minute jet, and an auxiliary fuel tank connected with the fuel supply pipe.

In testimony whereof I affix my signature in presence of two witnesses.

ORLANDO DUCKER.
